LACE

Frank H. Shepherdson, Philadelphia, Pa., assignor to North American Lace Company, Inc., Philadelphia, Pa.

Application February 13, 1956, Serial No. 40,123

Term of patent 3½ years

(Cl. D47—6)

The figure on the drawing is a plan view of a lace showing my new design on a dark background so as to bring out more clearly the details thereof.

I claim:

The ornamental design for a lace, substantially as shown and described.
